UNITED STATES PATENT OFFICE.

HENRY J. KASCH, OF DAYTON, OHIO, ASSIGNOR TO THE KURZ-KASCH COMPANY, OF DAYTON, OHIO, A CORPORATION OF OHIO.

DESIGN FOR AN INDICATOR MOUNTING FOR RADIO APPARATUS OR THE LIKE.

Application filed June 18, 1926. Serial No. 18,086. Term of patent 7 years.

To all whom it may concern:

Be it known that I, HENRY J. KASCH, a citizen of the United States, residing at Dayton, Montgomery County, Ohio, have invented a new, original, and ornamental Design for an Indicator Mounting for Radio Apparatus or the like, of which the following is a specification, reference being had to the accompanying drawing, forming a part hereof.

Fig. 1 is a front view and Fig. 2 is a side

elevation of an indicator mounting for radio apparatus or the like showing my new design.

I claim—

The ornamental design for an indicator mounting for radio apparatus or the like, substantially as shown.

In testimony whereof, I have hereunto set my hand this 10th day of June A. D. 1926.

HENRY J. KASCH.
